DESIGN.

—o—
J. L. FOLSOM.

CARPET.

No. 18,137.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,137, dated March 6, 1888.

Application filed January 26, 1888. Serial No. 262,060. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a number of conventionalized flower and leaf forms disposed over the surface of the carpet, as shown. The

flower forms are either circular or oval in character and occur singly or in groups of two or 20 three. These flower forms or groups are separated from one another by the leaf forms, which curve around between the flower forms. The flower forms have a central solid part encircled by long pointed flower-leaves. The 25 leaf forms are for the most part long and narrow, having a very irregular outline caused by small projecting leaves or leaf points.

What I claim as new, and desire to secure by Letters Patent, is—

The design for carpets, consisting of the design substantially as shown.

JAS. L. FOLSOM.
